CLAIM

The ornamental design for a vehicle cowl, as shown and described.

DESCRIPTION

FIG. 1 depicts a front, top, left perspective view of a vehicle cowl showing our new design.

FIG. 2 depicts a front, bottom, right perspective view thereof.

FIG. 3 depicts a front view thereof.

FIG. 4 depicts a back view thereof.

FIG. 5 depicts a left side view thereof.

FIG. 6 depicts a right side view thereof.

FIG. 7 depicts a top view thereof; and,

FIG. 8 depicts a bottom view thereof.

The ghosted or low contrasted showing of the vehicle cowl is provided for the purposes of illustrating portions that form no part of the claimed design. The dash lines depict boundaries of the claimed design.

1 Claim, 7 Drawing Sheets
